BOTTLE COLLAR

Charles J. Wolf, Jr., New York, N. Y., assignor to
 Polygraphic Company of America, Inc., New
 York, N. Y., a corporation of New York

Application October 12, 1938, Serial No. 234,688

5 Claims. (Cl. 40—4)

My invention relates to paper sheet collars to be slipped over and applied about the neck of a bottle for advertising purposes or for decorative use or to be supplied by the dairy to the customer and used by the customer for purposes of informing the delivery man as to the articles and quantities thereof to be left at the house of the customer.

The primary object of my invention is to provide a single integral piece of paper with a special form of medial slot to fit over the neck of the bottle and to so score the paper adjacent the ends of the slot as to insure the neat and proper creasing of the material of the collar at these points as to result in a very neat appearing collar, several of said score lines being so related and associated with said slot and the axially extending walls thereof as to constitute hinges upon which the paper flexes or bends with a lever action exerted by the special formation of said walls of the slot.

Another object of the invention is to provide the collar with high and wide skirts to afford ample room for advertising matter, decorative matter, instructions and the like.

The collar is designed and intended for use with the standard bottle having a large lower cylindrical portion, an upper relatively smaller neck portion, and an intermediate portion connecting the cylindrical portion to the neck portion and which intermediate portion may be of the standard tapered construction or may be of the so-called bell construction.

I provide a relatively wide and strong connecting marginal portion or bridge or hinge portion, whereby the collars may be applied quickly and with some force to the bottles by being slipped over the ends thereof, without fear of damage by tearing out the connecting marginal portions.

The connecting marginal portions stand out radially of the bottle in neat, well defined form and the skirt portions of the collar flare out radially slightly beyond the greatest diameter of the bottle to give an added decorative effect and also to attract special attention and avoid being confused or mistaken for the usual label definitely pasted to the bottles or to a bottle.

While the collar has been illustrated as applied to quart sized milk bottles, the invention is in no wise limited to use by dairies, but may be used on practically any bottle, such as ginger ale and other soft drink bottles, beer bottles, wine and other liquor bottles and practically with any tubular container having a tapered portion adjacent one end.

In the accompanying drawing:

Figure 1 represents a side elevation of a collar embodying my invention as applied to the upper portion of a bottle;

Figure 2, an end view, at right angles to Figure 1, of said collar as applied to said bottle;

Figure 3, a top plan view of Figure 1;

Figure 4, a sectional view on the line 4—4 of Figure 2, looking in the direction of the arrows; and

Figure 5, a plan view of a paper collar embodying my invention in its flat form prior to being applied to a bottle, said Figure 5 being drawn on a scale of four-ninths of actual size of an actual commercial specimen of my said collar.

All views of the drawing are made to a scale of approximately two-thirds of actual size, with the exception of Figure 5 which is made on the scale of four-ninths actual size, as above stated.

Referring now in detail to the drawing, A designates a quart size standard form milk bottle of the so called bell form; and B represents a quart size, so called cream top milk bottle, that is a bottle having a bulbous neck.

The bottle collar shown in Figures 1 to 5 inclusive is cut or stamped from a single sheet of preferably relatively heavy paper provided or formed with a long medial closed end slot 3 extending to the adjacent ends of the diverging scored lines 2, which scored lines 2 may be said to be imaginary continuations of the ends of the skirts 1, or in other words the scored lines 2 are in alignment with the respective slanting lines of the ends of the skirts 1.

The slot 3 separates the two segments or skirts 1 of the collar, which segments 1 are connected together at each end by the straps or bridges or marginal portions at the respective ends of the slot 3 and which respectively comprise the side portions 7 and the panel portion 6. Said connecting straps or bridges have their marginally outer edge portions arcuately outwardly curved and intersecting or merging with the end edges of the respective skirts substantially at the point where the respective score lines 2 merge with the end edges of the respective skirts, or in other words about at the center of the end portions of the skirts 1 or slightly thereabove. This results in providing an increase of paper material in the connecting straps and to this extent adding to their strength.

Two score lines 4 parallel to each other and to the central line of the slot 3 or substantially parallel thereto extend from the outer end of the slot 3 at each end thereof to the extreme marginal 55

edge of the respective connecting straps or bridges to define fold lines or hinge lines between the respective panels 1 of the connecting straps or bridges and the respective top panels 6 thereof.

5 The slot 3 is preferably formed with convex side walls 5 which approach closest to each other substantially at the center of the slot 3 and diverge in opposite directions from each other toward each end of the slot 3 on a gentle curve to 10 give what might be termed a double bell form of slot 3 and the respective score lines 4 are formed at points substantially medially disposed between the crests of the respective walls 5 and the end portions of said walls 5 respectively, so that as 15 the crests of the walls 5 engage and bear against the neck of the bottle they will be disposed slightly above their respective score lines 4 and will exert a leverage to force the respective skirt portions 1 and respective panels 7 to swing or hinge 20 or fold on the respective score lines 4, which are so located as to have the utmost freedom of action.

At the same time that this swinging or hinging action is taking place along the score lines 25 4 there will be a folding or swinging action on the respective score lines 2 to form the roughly or substantially triangular side panels 7, and in order to facilitate an easy and neat fold along the various score lines mentioned, the inner ends 30 of the score lines 4 will extend substantially inward to approximately the adjacent outer ends of the slot 3 and the score line 2 will intersect or substantially intersect with the respective score lines 4 at their respective inner ends.

35 To apply the bottle collars or paper collars to a bottle it is simply necessary to take a paper collar in the flat form illustrated in Figure 5 and to shove the same down over the neck of a bottle B, the neck of the bottle extending up 40 through the slot 3 and the different portions of the collar assuming the positions shown in Figures 1 to 4 inclusive by the spreading action of the neck and upper portion of the bottle. As thus applied to a bottle, the lower corners or 45 end portions 1' and the end edges thereof or of the skirts 1 will be spaced away from the face of the bottle and will extend radially outward beyond the greatest diameter of the bottle, all as well illustrated in Figures 1, 3 and 4 and will 50 act as a visual sign to call attention to the fact that the collar is not the usual label pasted on the front of the bottle, but carries a special message or advertisement. Further, by so extending beyond the face of the greatest diameter of 55 the bottle it will serve as a dress-up feature or ornamentation and to this end if desired the edge or marginal portion of the collar may be scalloped, ruffled or gilded or otherwise ornamented.

I claim:

60 1. A bottle collar consisting of a sheet of flexible material formed with a medial elongated closed slot, and comprising two opposed skirt portions separated by said slot and two connecting strap portions respectively disposed at the 65 respective ends of said slot and serving to connect the respective end portions of the skirts on opposite sides of said slot, said slot functioning to receive a bottle neck, the side walls of said slot being of convex outline and approaching each other most closely at their respective crests, the margins of said strap portions being convex 70 to provide additional material to strengthen the straps, diverging score lines being formed in the flexible sheet at the respective points of juncture 75 between the respective straps and respective

skirts and respectively being in alignment with the slanting end edges of said skirts, said straps each having a parallel pair of score lines formed therein and extending from the respective ends of said slot to the adjacent margin of the strap, 5 each said score line of said pair being located between the crest and lowest point of the adjacent wall of the slot to act as a hinge for the adjacent skirt and panel of the strap to swing on under the influence of the leverage of the crest 10 of said adjacent slot wall and the spreading action of the bottle neck, the construction and relation of parts causing the respective connecting strap portions to neatly fold along the parallel and diverging score lines to form a top panel 15 and two substantially parallel side portions and to cause the ends and lower corner portions of the skirt portions to project outward away from the face of the bottle to focus attention on the collar. 20

2. A bottle collar consisting of a sheet of flexible material formed with a medial elongated closed slot, and comprising two opposed skirt portions separated by said slot and two connecting strap portions respectively disposed at the 25 respective ends of said slot and serving to connect the respective end portions of the skirts on opposite sides of said slot, said slot functioning to receive a bottle neck, the side walls of said slot being of convex outline and approaching 30 each other most closely at their respective crests, the margins of said strap portions being convex to provide additional material to strengthen the straps, diverging score lines being formed in the flexible sheet at the respective points of juncture 35 between the respective straps and respective skirts and respectively being in alignment with the slanting end edges of said skirts, said straps each having a parallel pair of score lines formed 40 therein and extending from the respective ends of said slot to the adjacent margin of the strap, and each said score line of said pair being located between the crest and lowest point of the adjacent wall of the slot to act as a hinge for the adjacent skirt and panel of the strap to swing on 45 under the influence of the leverage of the crest of said adjacent slot wall and the spreading action of the bottle neck. 50

3. A bottle collar consisting of a sheet of flexible material formed with a medial elongated closed slot, and comprising two opposed skirt portions separated by said slot and two connecting strap portions respectively disposed at the 55 respective ends of said slot and serving to connect the respective end portions of the skirts on opposite sides of said slot, said slot functioning to receive a bottle neck, the side walls of said slot being of convex outline and approaching each other most closely at their respective crests, the margins of said strap portions being convex 60 to provide additional material to strengthen the straps, diverging score lines being formed in the flexible sheet at the respective points of juncture between the respective straps and respective skirts and respectively being in alignment with 65 the slanting end edges of said skirts, said straps each having a parallel pair of score lines formed therein and extending from the respective ends of said slot to the adjacent margin of the strap, each said score line of said pair being located at 70 a greater distance from the central longitudinal line of said slot than is the crest of the adjacent side wall thereof. 75

4. A bottle collar consisting of a sheet of flexible material formed with a medial elongated

- closed slot, and comprising two opposed skirt portions separated by said slot and two connecting strap portions respectively disposed at the respective ends of said slot and serving to connect the respective end portions of the skirts on opposite sides of said slot, said slot functioning to receive a bottle neck, the margins of said strap portions being convex to provide additional material to strengthen the straps, diverging score lines being formed in the flexible sheet at the respective points of juncture between the respective straps and respective skirts and respectively being in alignment with the slanting end edges of said skirts, said straps each having a parallel pair of score lines formed therein and extending from the respective ends of said slot to the adjacent margin of the strap.
5. A bottle collar consisting of a sheet of flexible material formed with a medial elongated closed slot, and comprising two opposed skirt portions separated by said slot and two connecting strap portions respectively disposed at the respective ends of said slot and serving to connect the respective end portions of the skirts on opposite sides of said slot, said slot functioning to receive a bottle neck, the margins of said strap portions being convex to provide additional material to strengthen the straps, diverging score lines being formed in the flexible sheet at the respective points of juncture between the respective straps and respective skirts and respectively being in alignment with the slanting end edges of said skirts.
